Application filed September 27, 1895. Serial No. 563,935. Term of patent $3\frac{1}{4}$ years.

To all whom it may concern:

Be it known that I, CHARLES BOOZ, a citizen of the United States, residing at Buffalo, in the county of Erie and State of New York, have invented and produced a new and original Design for Wall-Paper, of which the following is a specification, reference being had to the accompanying drawing, showing a part thereof.

The design consists of a series of ornamental figures formed of ornamental scrolls with a torch-shaped ornament in the center connected with the ornamental scrolls by bows of ribbon, and open ornamental wreaths with an upright ornament formed of ornamental scrolls in the center of the open wreaths and arranged in alternate rows with the ornamental figures, and ribbon festoons connecting said wreaths and ornamental figures, as represented in the accompanying drawing.

The border of said design is formed of simi-

lar ornamental figures with a torch-shaped ornament in the center and ornamental scrolls connected with said torch-shaped ornament by bows of ribbon, said ornamental figures being placed at certain distances apart and connected by lines or festoons of flowing ribbon, an ornamental band at the top and bottom of said border, and a horizontal line of small ornaments run through the center of said border, as shown in the drawing.

What I claim is—

1. The design for wall paper herein shown and described.
2. In the design for wall paper, the border herein shown and described.

Witness my hand this 24th day of September, 1895.

CHARLES BOOZ.
